UNITED STATES PATENT OFFICE.

ERNEST E. MALLORY, OF WEST UNITY, OHIO.

UMBRELLA.

SPECIFICATION forming part of Letters Patent No. 612,045, dated October 11, 1898.

Application filed November 19, 1897. Serial No. 659,198. (No model.)

To all whom it may concern:

Be it known that I, ERNEST E. MALLORY, a citizen of the United States, residing at West Unity, in the county of Williams and State 5 of Ohio, have invented certain new and useful Improvements in Umbrellas; and I do hereby declare the following to be a full, clear, and exact description of the invention, such as will enable others skilled in the art to 10 which it appertains to make and use the same.

My invention relates to improvements in umbrellas, more especially in what may be termed "short-folding" umbrellas. Desiderata in this class of umbrellas are to provide for the compact folding thereof, to economize space to a nicety in packing or folding the same with facility and convenience in a prescribed compass—as, for instance, in carrying the umbrella in a hand or "gripsack" 15 or, similarly, in traveling or itinerating from place to place; also, to provide for readily repairing the umbrella, and to adapt the umbrella to be as readily unfolded or put back 20 into its previous shape when required for use. Incidentally the umbrella stick or staff is adapted to be withdrawn or detached from the "tip" or cover when short-folded for use as a walking stick or cane, as will be readily 25 appreciated.

Further objects of my invention are to dispense with the cup-shaped crown-piece and to adapt the ribs to provide for the ready housing of the parts folding contiguously 35 thereto in short-folding the umbrella, to remove all strain from the various parts in their short-folded position, and to so hinge or articulate the rib-sections as to provide substantially continuous ribs with no irregularities 40 therein, and therefore allow the cover to have a smooth regular surface throughout at the hinge-joints and elsewhere.

Additional advantages of my invention will appear from the description of the details 45 of the construction and arrangement of the parts.

The invention consists, primarily, of a sectional runner having in one section—the relatively stationary one—a loose dog or detent 50 and a spring connected to the sliding or movable runner-section adapted to engage said dog or detent for holding the runner at either

of the prescribed points, according as the umbrella is open, closed, or folded in the ordinary way or folded short; secondly, of short 55 pivoted rib-sections between the upper ends of the ribs proper and the notch adapted when the umbrella is short-folded to stand at an angle of about forty-five degrees to the notch and to close down with the inward folding of 60 the ribs proper and the cover in the ordinary way, and, thirdly, of articulated or hinge-joint sections between the primary rib-sections where they fold with the cover in folding short. 65

The invention also consists of certain other parts and details of the construction and arrangement of the same, all substantially as hereinafter more fully disclosed, and specifically pointed out in the claims. 70

The scope of my invention, broadly considered, extends to means for adapting the runner specially for use with a short-folding umbrella as well as the ordinary long-folding umbrella, said means comprising a runner 75 having a sliding section adapted to act upon a detent or dog through the action of a spring to engage the respective kerf or recess in the staff or stick at either the point for holding the umbrella open or closed, also whereby 80 the detent or dog will be permitted to be entirely disengaged from the staff in short-folding the umbrella; to means to automatically cause the ribs to coöperate with the ordinary long-folding umbrella-notch to adapt it for a 85 short-folding umbrella notch or crown, and to means to produce the hinge or joint in alinement with the primary sections of the ribs. 90

All matters pertaining to the details of construction for putting into execution the foregoing are treated as only means to an end, and therefore can be changed to suit circumstances. 95

In the accompanying drawings, illustrating 100 the preferred or one form of carrying out my invention, Figure 1 is a side view of the umbrella in its long-folded form. Fig. 2 is a view showing it open. Fig. 3 is a sectional view showing it short-folded. Fig. 4 is an enlarged partly-broken-away view showing the stick or staff withdrawn from and relatively disposed to the tip. Fig. 5 is an enlarged detailed view showing more fully the short sub-

sections of the ribs. Fig. 6 is a similar view of one of the articulated hinge-joint sections, and Fig. 7 is a view of the same with the lock therefor. Fig. 8 is an enlarged view of the 5 runner with its detent or dog, a portion of the staff or stick also being shown. Fig. 9 is a sectional view of the same with the sliding section thereof moved to another point. Figs. 10, 11, and 12 are details showing the different 10 adjustments of the staff and its handle. Fig. 13 is an enlarged detail view of clasping 15 strap or band for cover.

A is the staff or stick, A' the tip, B the cover, C the ribs, D the notch or crown, E the runner, and F the stretchers, all the general features of an umbrella.

The ribs C are, as usual in this class of umbrellas, made in two principal sections *c' c'* and have suitably attached thereto in the ordinary way the cover B to permit the folding of the latter upon itself, as practiced in short-folding the umbrella, the upper centering portion of said cover being secured around the tip A' and having fitted thereon a cap *a*, held securely in position in any suitable way. 20 The ribs C have their upper or inner sections *c'* provided with short pivoted or articulated subsections or links *c²*, adapted to abut squarely against the notch or crown D to 25 cause them to stand either radially thereto when the umbrella is open or at right angles to said notch when the umbrella is short-folded, said short subsections being wired to said notch, as is now usually done in securing 30 the upper rib-sections to the notch or crown of an umbrella. By this arrangement, the short subsections or links *c²* thus adapted to extend out about at an angle of forty-five degrees from the stick or staff, as just intimated, 35 keeping the cover spread to that extent, I provide for holding the inner ends of the upper rib-sections proper away from the notch or crown when the umbrella is inverted and folded short, thus providing for the housing or assembling of the inner ends of the 40 runner-fingers with the attached or inner ends of the stretchers. This dispenses with the use of the additional or dome-shaped crown or notch heretofore employed for that purpose; 45 also, when the umbrella is folded long the parts are more presentable or neat, tapering direct from the tip and crown, and thus adapted to be more compactly and symmetrically folded.

50 The cover is also connected to the upper rib-sections in any suitable manner—as, for instance, by sewing or looping it to eyes *c^x* upon the under side of said rib-sections, as shown, or otherwise—to prevent the folding 55 back of the cover at that point as the umbrella is short-folded.

For clasping the cover of the umbrella, either short-folded or long-folded, in a compact form I employ a strap or band *B'* of 60 some suitable material—such, for instance, as elastic ribbed gore, as commonly used for that purpose. The said strap or band is

passed through an eyelet *b*, clenched in the cover, and having two hooks or clasps *b' b²* arranged upon opposite sides thereof and at 70 diametrically opposite points. The band or strap *B'*, though in a single piece, is knotted, as at *b³*, or otherwise adapted to provide a shorter length or portion thereof on one side of said eyelet or cover and a longer portion on the opposite side of the latter and having eyes or rings *b⁴ b⁵* at its ends, said rings or eyes adapted to engage said clasps or hooks *b' b²*, respectively, the whole length of said strap being used when the umbrella is short-folded and the long portion of said strap being used when the umbrella is long-folded.

The principal rib-sections *c' c'* have sandwiched in between their opposed ends articulated or hinge-joint sections *c³*, adapted to 85 permit the lower rib-sections to fold back upon the upper rib-sections as the umbrella is short-folded. The hinge-joint sections *c³* consist each of a short piece with edgewise-disposed end portions or tongues fitted and pivoted in corresponding slots or recesses in the respective rib-sections and with lateral offsets *c⁴*, having inclined shoulders *c⁵* abutting the corresponding ends of said rib-sections to allow the latter to flex or fold outward, but prevented from folding inward. 90 The lower rib-section has a projection *c⁶* extending from its lower side up under the upper rib-section adapted to serve as a bearing for the cam end of the stretchers F, with said cam end suitably hung between lugs or ears *c⁷*, depending from the sides of the upper rib-section. This arrangement provides for locking the lower rib-sections at the hinge-joints against upward displacement or folding from 95 the action of the wind or otherwise accidentally when the umbrella is in use or when long-folded. It will be noticed that the rib-sections thus jointed or hinged together present 100 a practically-continuous rib without upstanding hinge-joints, thus allowing the cover to 105 lie smoothly throughout.

The runner E has outstanding therefrom a series of radial brackets or arms *e*, formed, it may be, upon a hub of spider-like form and 110 sleeved upon the runner proper fixedly. To the outer, preferably upwardly-projecting, end portions of the arms *e* are pivoted a series of spring-fingers *e'*, two being applied to each arm, and one each of said spring-fingers of 115 each two arms being connected to the inner end of each stretcher. Said spring-fingers are presented edgewise to the staff or stick, which, together with this manner of connection between said fingers and stretchers, provides for the reception of the stretchers, and 120 the upper rib-sections between said fingers and arms when the umbrella is short-folded effecting the compact folding of the parts 125 with convenience and facility.

The spring-fingers *e'* are compassed by a sliding runner-section *E'*, of spider-like form, being composed, preferably, of a central ring *e²*, arranged on the runner proper, and having 130

a series of radial sector - like arms e^3 , each adapted to embrace two spring-fingers, whereby by the sliding thereof, say upward, said spring-fingers are pressed from the staff or 5 stick, relatively lengthening the stretchers, as required when the umbrella is open or in use, and to stay the spring-fingers against being flexed or yielding when the umbrella is subjected to the action of the wind. The opposite 10 site movement of the sliding runner-sections E' releases the spring-fingers, as is resorted to in short-folding the umbrella.

Two opposite lever-clasps f^4 are suitably pivoted upon opposite arms e of the runner 15 E, with their lower ends bifurcated to clear said arms as their lower ends are swung inward to engage and elevate the sliding runner-section E', as is done, as above stated, when the umbrella is opened to compress the 20 spring-fingers. These clasps are curved at their upper ends, permitting said ends to overhang the runner, and are provided with notches or recesses f^5 , one in each clasp or lever, adapted to embrace the opposite sector-like arms e^3 of the sliding runner-section E' to provide for holding the latter at its point of adjustment or against sliding downward. It is remarked, however, that the clasps are 25 not essential to hold the sliding runner-section against movement, as the latter is enabled to secure a firm grip upon the spring-fingers from the resistance offered thereto, due in a measure to the action of the spring-fingers upon said sliding runner - section. 30 These clasps, nevertheless, afford a convenient means or finger-holds when thrown down or disengaged from the sliding runner-section for readily pulling down the runner in unfolding the umbrella after having been short-folded, in addition to effecting the elevation 35 of the runner, as previously stated, in short-folding the umbrella.

In a raised-edged slot g in the tubular portion of the runner E, as one way of carrying 40 into effect this part of my invention, is arranged loosely, preferably, an edgewise-disposed piece of steel g' , having a tooth g^2 , its engaging end serving as a dog or detent to engage the required notches or kerfs h^1 in 45 the staff or stick A for holding the runner instead of by a catch on the stick or staff, as heretofore, at the required point of adjustment—as, for instance, when the umbrella is open or long-folded. To the sliding runner 50 E' is connected one end of a spring g^3 , preferably bail-like, having its free end adapted to bear upon said dog or detent at either end—at one end when the runner is in the position it occupies when the umbrella is open and at 55 the other end when the runner is in the position it occupies when the umbrella is long-folded. This arrangement of parts dispenses with the use of two stops or catches, as now used on the ordinary umbrella staff or stick, 60 as will be readily appreciated.

It will be seen that as the sliding runner-section E' is moved outward or downward, as

is done preparatory to the short-folding of the umbrella, the spring g^3 is so adjusted as to cause it to bear upon the loose detent or dog g^2 at its untoothed end and elevate its toothed end and so retain said end, and thus provide for retracting the tooth of the dog or detent from the lower kerf or recess in the staff or stick and retain it out of engagement 70 with the staff or stick during the entire transit of the runner E from its two extremes of adjustment—i. e., from the position it occupies when the umbrella is long-folded to that it takes in short-folding the umbrella. 80

The staff or stick A, in addition to being made in extensible and contractible sections for the obvious purpose of adapting it for this class of umbrellas in case it is desired to also fold it with the short-folding of the umbrella, is also adapted to be withdrawn or detached from the cover and other parts of the umbrella in case it is desired to use it in the meantime as a walking stick or cane. To these ends the tip A' is made of a tube A^2 , 90 having opposite bayonet-like ended slots a^2 , and upon this tube is sleeved a second tube a^3 , formed with the before-referred-to notch D and with a flange or crown a^4 overhanging said notch to prevent possible upward displacement of the wired inner ends of the rib-sections. The tube or sleeve a^3 also has opposite slots a^5 , the slots a^2 being adapted to be brought into alignment or coincidence therewith by grasping and holding the staff 95 stationarily and turning the tip slightly to the left.

The extreme lower end of the tip-tube A^2 has a shoulder a^4 thereon to confine it to the notch-tube or sleeve a^3 , and the extreme upper end portion of the staff or stick A is reduced, as at a^6 , to permit it to be inserted into the tip-tube and its shoulder formed by such reduction caused to engage or abut the inner end of the notch-tube and has a pin a^8 110 passing transversely through it, with its ends projecting therefrom to engage the bayonet-slots of said tip-tube. By bringing the slots a^2 and a^5 into coincidence, as above pointed out, the projecting pin ends can be withdrawn with the reduced end of the staff or 115 stick from the tip.

The uppermost section A^3 of the staff or stick A has, as usual, a pivoted or articulated link connection A^4 with the next section A^5 120 thereof to permit the same doubling up or folding upon itself, and over this link connection is adapted to slide a sleeve A^6 when the parts are extended. The section A^5 , the longest, which has a recess or kerf extension 125 of the lower kerf or recess h' , telescopes a sleeve-section A^7 , having the kerf or recess h'' , adapted by the proper adjustment of the parts to be brought into coincidence with the aforesaid recess or extension thereof, and also 130 has an aperture a^9 clear through it adapted to register with opposite or coincident apertures a^9 in the sleeve-section A^7 to permit of the application thereto of a handle A^8 . The

handle A⁸ has a spring-pressed detent or dog a¹⁰, adapted to engage the apertures a⁸ a⁹, effecting the detachable connection of the handle and the sleeve-section A⁷, also the section 5 A⁵ and said sleeve-section A⁷. The sleeve-section A⁷ has near its upper end a socket or cup-like sleeve a¹¹, with a stud arranged therein adapted to engage a corresponding recess a¹² in the edge of said handle to provide for the alinement of the recesses and apertures aforesaid as the parts are extended. This arrangement also permits of the interchangeability of handles, an example of two of which adapted to be applied to the stick or staff 10 is disclosed in the drawings. When the handles are removed, a cap a¹³ or other closure may be applied to the end of the lowermost or sleeve section, as desired.

In order to short-fold the umbrella, it is inverted, the tip resting on the floor. It is assumed that the runner E is in its normally innermost position. The sliding runner-section E' is moved downward, the lever-clasps f f having been previously disengaged from 20 said runner-section, permitting the relative shortening of the stretchers, as required. The same movement of said runner-section effects the adjustment of the spring g³ with relation to the dog or detent g' g², so as to retract the latter from its engaged lower recess or kerf h' in the staff. The normally lower rib-sections, with that portion of the cover, are folded outward and back upon the other portion of the cover and rib-sections, the aforesaid relative shortening of the stretchers allowing this. The runner, with the spring-fingers, is now run clear down to the notch or crown, carrying with it the inner ends of the stretchers, when by properly compassing the cover with the hand the parts will assume a 30 compact folded position.

The numerous features of my invention which commend its merits are fully disclosed in the foregoing. Among these may be mentioned compactness or nicety of folding of the parts—greatly desirable and an indispensable prerequisite in packing the same in a hand or grip sack, as found convenient in traveling or itinerating from place to place or making a tour—facility and convenience in the conversion of the umbrella into either a short-folding or long-folding form, as may be desired, and the ready detachability of the staff or stick of the umbrella for use as a walking stick or cane, constituting it a thing of continuous utility, and still further providing for greater compactness in lessening the number of parts of the umbrella for folding. It is also capable of being readily repaired when 40 such becomes necessary, as is made apparent.

It will be understood that I do not restrict myself to the construction and arrangement of the parts as to minutia of detail; but such may be changed or modified, as required, without departing from the spirit or principles of my invention and the same remain intact.

Having thus fully described my invention, what I claim, and desire to secure by Letters Patent, is—

1. In an umbrella, the combination, with 70 the ribs, stretchers and staff, of the runner carrying a sliding or movable section and a dog or detent set loosely in said runner and having, suitably spaced apart, studs or projections adapted to form separate fulcrums 75 therefor, and a spring carried by said sliding or movable runner-section, adapted to bear upon said dog or detent, substantially as set forth.

2. In an umbrella, the combination, with 80 the crown or notch, stretchers and staff or stick, of the sectional ribs, having pivoted subsections at the inner or upper ends, in turn pivoted to said crown-notch, with their crown or notch connected ends adapted to abut 85 squarely against said crown or notch to aid in housing the inverted ends of the primary rib-sections when the umbrella is short-folded, substantially as set forth.

3. In an umbrella, the combination, with 90 the staff and stretchers, of the sectional ribs having their primary sections connected by articulated sections or links let into said primary sections or links flush with the upper surface of said ribs and having lateral inclined offsets 95 abutting corresponding shoulders or ends of said primary sections, one of said primary sections having an extension underlapping the joint thus formed between said primary sections and said stretchers adapted at their 100 rib-connected ends to bear upon, and lock, said underlapping rib extension in place, substantially as specified.

4. In an umbrella, the combination, with 105 the notch, the stretchers and the staff or stick, of the sectional ribs having their primary sections connected by hinge-joint or articulated sections or links let into the rib-sections flush with the upper surface of said ribs and having lateral offsets with inclined shoulders 110 abutting corresponding ends of said rib-sections, substantially as set forth.

5. In an umbrella, the combination, with 115 the notch or crown, staff or stick and stretchers, of the sectional ribs each having its primary sections in alinement, end to end, and the intermediary subsections or links sandwiched between the said primary sections flush with the upper surface of said primary rib-sections, one of said primary rib-sections having an extension underlapping the intermediary joint thus formed and stretchers having their rib-connected ends adapted to bear upon, and lock, said rib extension in place, 120 substantially as set forth.

6. In an umbrella, the combination, with 125 the ribs, stretchers and staff or stick, of the runner having spring-fingers connected to said stretchers and having a sliding or movable section fitted upon or compassing said 130 spring-fingers, substantially as described.

7. In an umbrella, the combination, with

the ribs, the notch or crown, the stretchers and stick or staff, of the runner comprising the series of radial arms having attached to their upstanding ends edgewise-arranged 5 spring-fingers, in turn connected to said stretchers, the sliding runner-section compassing said spring-fingers and carrying a spring bearing upon a detent or dog loosely set in a slot in said runner, substantially as 10 specified.

8. In an umbrella, the combination, with the tubular tip portion having the notch or crown tube or sleeve, adapted to turn in the latter, of the staff or stick having lateral projections, both said tip and sleeve having slots adapted to be interlocked with said projections of said staff, substantially as described.

9. In an umbrella, the combination of the frame composed of the usual elements of an umbrella and the stick or staff comprising two main linked or jointed together sections 20 suitably sleeved at the joint, and the sleeve-section telescoping one of the aforesaid sections and having coincident recesses and 25 apertures, and a socket having a stud therein, and the handle provided with a spring detent or dog engaging said coincident apertures and

a recess in one edge to engage said stud, substantially as set forth.

10. In an umbrella, the combination, with 30 the cover having an eyelet therein, of the clasping strap or band having different lengths beyond said eyelet or cover upon opposite sides thereof, respectively, and rings or eyes at its ends adapted to engage said 35 clasps upon opposite sides of said eyelet, at diametrically opposite points, substantially as set forth.

11. In an umbrella, the combination, with 40 the stretchers and runner having the spring-fingers connected to said stretchers, the ribs, the stick or staff and the sliding runner-section, of the lever-clasps pivoted upon said runner and adapted to engage said sliding runner-section, and to be swung downward 45 and grasped, for moving said runner downward, substantially as set forth.

In testimony whereof I affix my signature in presence of two witnesses.

ERNEST E. MALLORY.
